BOTTLE

Ronald H. Dallas, South Gate, Calif., assignor to
Cella Vineyards, Reedley, Calif., a corporation
of California

Application June 3, 1953, Serial No. 25,298

Term of patent 14 years

(Cl. D58—8)

To all whom it may concern:

Be it known that I, Ronald H. Dallas, a citizen of the United States, residing in South Gate, in the county of Los Angeles and State of California, have invented a new, original, and ornamental Design for a Bottle, of which the following is a specification, reference being had to the accompanying drawing, forming part thereof.

Fig. 1 is a side elevational view of a bottle, showing my new design.

Fig. 2 is a fragmentary cross-sectional view thereof taken on the line 2—2 of Fig. 1.

Fig. 3 is a fragmentary cross-sectional view thereof taken on the line 3—3 of Fig. 1.

The sides not shown are the same as the sides shown.

The dominant features of the design reside in the portions shown in full lines in the drawing.

I claim:

The ornamental design for a bottle, substantially as shown and described.

RONALD H. DALLAS.
